UNITED STATES PATENT OFFICE.

JAMES H. FOOTE, OF CINCINNATI, OHIO.

SASH-CORD PULLEY.

1,029,005.

Specification of Letters Patent.

Patented June 11, 1912.

Application filed December 20, 1911. Serial No. 666,898.

To all whom it may concern:

Be it known that I, JAMES H. FOOTE, a citizen of the United States, residing at Cincinnati, in the county of Hamilton and

5 State of Ohio, have invented certain new and useful Improvements in Sash-Cord Pulleys; and I do hereby declare the following to be a full, clear, and exact description of the same, reference being had to the accompanying drawings, forming part of this specification, and to the figures and letters of reference marked thereon.

This invention relates to sash cord pulleys of that type adapted to be inserted and seated in the window framing without the employment of screws or similar framing penetrating fastening devices, thus making it only necessary to prepare the framing with the slot opening for the reception of 20 the pulley casing.

The form of pulley adopted for illustrating the invention is one more especially designed for use at the upper ends of the stiles of the framing, or in immediate proximity 25 to the head of the framing, although features of the invention are applicable to pulleys adapted for being located at any point in the side or stile of the window framing.

Referring to the drawings,—Figure 1 is 30 a section in a vertical plane through a sash cord pulley embodying the present improvements mounted in position in a window framing, the latter being also shown in section; Fig. 2 is a section in a horizontal plane indicated by the line 2—2 of Fig. 1 looking 35 downwardly; Fig. 3 is a detail front elevation of the upper portion of the pulley; Fig. 4 is a corresponding rear elevation with the pulley mounted in position in the framing; Fig. 5 is a sectional view corresponding to 40 Fig. 1, but illustrating a modified form of keeper with a face plate formed as an integral part thereof.

Like letters of reference in the several figures indicate the same parts.

The sheave bearing casing of the pulley forming the present invention is illustrated in the accompanying drawings as an integral casting, but it will be understood that 50 it may be formed of sheet metal by well known processes now in common use. It is provided with two substantially parallel walls A between which the sheave B is journaled and at top and bottom it is provided 55 with extensions or projections, the top ex-

tension or projection being indicated by the reference letter C and the bottom extension by the reference letter D. The top extension C may be formed by portions of the side walls A and is provided with a rearwardly directed face c, while the bottom extension D is provided with a forwardly directed face d, these two faces being preferably in substantially the same vertical plane and are adapted to coöperate with faces on the window framing. The face d seats against the inner side of the framing F, while the face c seats against the rear side of a recess f in the head f' of the framing. The top extension is of greater length than the bottom extension D, and consequently the whole sheave bearing casing may be inserted in its opening in the window framing by passing the top extension up into the recess f a sufficient distance to permit the bottom extension D to pass through the slot, whereupon by a bodily downward movement of the casing it will seat itself in the window framing, the bottom extension preventing any outward movement at the lower end, and the top extension preventing any inward movement of the upper end. To hold the casing down to its seated position, the top extension C is provided with a rearwardly extending shoulder or offset c' which is adapted to pass under the inner wall of the recess f, as shown clearly in Figs. 1 and 5, if necessary, sufficient force being exerted upon the upper end of the casing to force the projection or projections c' into the wood of the head of the window framing. The forward or outer side of the extension C is, as shown, preferably in rear of the vertical plane of the front of the sheave bearing casing, whereby the whole extension C, including the shoulder or offset c', may be passed up into the recess f while the pulley is being placed in position, and when the pulley is in position a keeper is inserted in front of the projection or extension C, so as to hold the sheave bearing casing back in its vertical position, with the shoulders or offsets c' beneath the rear wall of the recess. This keeper, as shown in Fig. 1, may consist of a piece of sheet metal H, the front portion of which may lie substantially flush with the front of the sheave bearing casing, while a rearwardly extending portion h is adapted to bear against the extension C and to be positioned by a shoulder or stop c² on 110

the front of the extension. The form of keeper shown in Fig. 1 is adapted to occupy the recess in front of the extension C, but it is obvious that the said keeper might be 5 extended to form a face plate $\bar{I}$ as indicated in Fig. 5, in which instance it is provided at its lower end with an inwardly extending tongue or catch i which will take over a transverse bar or projection i' in the sheave 10 bearing casing, so as to hold the keeper and face plate firmly in position after the casing has been inserted in the window framing.

In front of the bottom extension D the 15 lower end or face of the sheave bearing casing is preferably inclined downwardly and forwardly, as at d' whereby when seated it will prevent any inward movement of the lower end of the casing, this inclined face 20 also operating in a measure with a tendency to hold the lower portion of the sheave bearing casing out to its proper position with the extension D firmly seated against the inner face of the framing.

25 At the front each side wall A is provided with a transverse rib or flange a serving to fill the slot or opening in the window framing, and thereby give a good face finish, and it is preferred that these ribs or flanges shall 30 seat slightly in the side walls of the slot in the window framing to thereby not only position the sheave bearing casing centrally in said slot and form a tight fit, but also prevent bodily inward movement of the sheave 35 bearing casing, whereby any danger of the said casing dropping into the weight box is obviated.

In inserting the sheave bearing casing in the window framing, the top extension is 40 passed up into the recess f as indicated by dotted lines in Fig. 5, then the lower portion is swung in and the whole casing allowed to move bodily downward until it seats at the bottom of the slot in the framing, and the upper end is pushed back until the shoulders or offsets c' pass beneath the inner wall of the recess f thereby holding the device firmly down to its seat. The keeper is then inserted in front of the top 45 extension C and its lower end swung down into position indicated in full lines in Figs. 1 and 5. Where a short keeper, as shown in Fig. 1, is employed, it is preferably provided with an aperture h' through which a suitable 50 instrument may be passed for removing the keeper, should it be necessary at any time to take the pulley out of the window framing.

Having thus described my invention, what I claim as new and desire to secure by Letters Patent of the United States, is:—

1. A sash cord pulley embodying a sheave bearing casing having an extension at the top adapted to enter a recess in the framing whereby it is held against escape toward 65 front and rear and a projection at the bot-

tom on the inner side of the casing of less length than the top extension and adapted to seat against the inner side of the framing, whereby the bottom projection may be passed through the framing and seated 70 against the inner side thereof without withdrawing the top extension from its recess, means for preventing the bodily upward movement and for preventing the inward movement of the bottom of the casing when seated in the framing. 75

2. A sash cord pulley adapted to be seated in the window framing by a bodily downward movement, embodying a sheave bearing casing having an extension at the top 80 adapted to enter a recess in the framing, whereby it is held against escape toward the front and rear, a projection at the bottom on the inner side of less length than the top extension and adapted to seat 85 against the inner side of the framing whereby the bottom projection may be passed through the framing and seated against the inner side thereof without withdrawing the top extension from its recess, a movable 90 keeper supported by the casing in front of and co-operating with the top extension, and means for preventing bodily upward movement and for preventing the inward movement of the bottom of the casing when 95 seated in the window framing.

3. A sash cord pulley adapted to be seated in the window framing by a bodily downward movement, embodying a sheave bearing casing having extensions at the top and bottom, with rearwardly and forwardly directed faces respectively in substantially the same plane, a shoulder on the top extension projecting in rear of said plane for holding the casing down to its seat, means on the 105 casing for limiting its inward movement at the lower end, and a movable keeper co-operating with the outer side of the top projection. 100

4. A sash cord pulley adapted to be seated 110 in the window framing by a bodily downward movement embodying a sheave bearing casing having extensions at the top and bottom with rearwardly and forwardly directed faces respectively in substantially the 115 same plane, the top extension having its forwardly directed face in a plane in rear of the plane of the front of the casing, and a movable keeper located in front of and co-operating with the top extension. 120

5. A sash cord pulley adapted to be seated 125 in the window framing by a bodily downward movement embodying a sheave bearing casing having extensions at the top and bottom with rearwardly and forwardly directed faces respectively in substantially the same plane, the top extension having a rearwardly extending shoulder for holding the casing down in its seat and a forwardly directed face in rear of the plane of the front 130

of the casing, and a movable keeper located in front of and coöperating with the top extension.

6. A sash cord pulley adapted to be seated in the window framing by a bodily downward movement embodying a sheave bearing casing having on the inner side at the bottom a downwardly extending projection adapted to seat against the inner side of the window framing, and a downwardly and forwardly inclined face in front of said projection adapted to seat in the window framing and resist inward movement of the bottom of the casing, and an upwardly extending projection at the top of the casing of greater length than the bottom projection whereby the casing may be seated by a bodily downward movement without freeing the top projection from the framing above the casing.
7. A sash cord pulley adapted to be seated in the window framing by a bodily downward movement embodying a sheave bearing casing having extensions at top and bottom with rearwardly and forwardly directed frame engaging faces respectively in sub-

stantially the same plane, the top extension having a rearwardly extending shoulder for holding the casing down to its seat and the bottom of the casing in front of the bottom projection being inclined forwardly and downwardly to hold the bottom of the casing against inward movement.

8. A sash cord pulley adapted to be seated in the window framing by a bodily downward movement, embodying a sheave bearing casing having extensions at top and bottom with rearwardly and forwardly directed frame engaging faces respectively in substantially the same plane, the top extension having its forwardly directed side in a plane in rear of the plane of the front of the casing, and a face plate having an inwardly projecting tongue engaging the bottom of the casing and a projection at the upper end coöperating with the front of the top projection of the casing.
